CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK.

SPEED-CONTROL SYSTEM.

Application filed March 16, 1922. Serial No. 544,265.

This invention relates to train control ties of this invention, it has been illustrated 55 systems, and more particularly to an arrangement of parts and circuits for making an automatic brake application dependent 60 upon the time taken by a train in passing between two control points. In certain types of 65 train control systems where it is desired to make the automatic control dependent upon the speed of the train, it has been proposed 70 to utilize a time-distance interval principle for determining when the train's speed is excessive and a brake application should be given. In this type of system, to which the present invention more particularly relates, 75 10 a suitable timing mechanism is employed, preferably on the train, and this timing mechanism is started or rendered effective, as the train passes the first or initiating control point, and automatically returns to 80 its initial or normal condition after the lapse of a predetermined time interval. Obviously, it is essential that such timing mechanism be accurate, efficient, and reliable 85 in its performance; and one of the principal 90 20 objects of this invention is to devise an organization of parts and circuits by means of which the desired intervals of time may be automatically measured, and with which any failure of an essential part will be on 95 25 the side of safety.

Various other specific objects, advantages, and characteristic features of the invention will appear hereinafter, as the description progresses.

30 In the accompanying drawings, Figure 1 illustrates in a conventional and diagrammatic manner the trackway equipment for a train control system embodying this invention; and

35 Fig. 2 shows in a simplified and diagrammatic way parts and circuits of the car equipment, these parts and circuits being shown more with the purpose of facilitating explanation, than with the idea of 40 showing the specific construction and arrangement of parts preferably employed in practice.

The present invention deals more particularly with the construction and manner of 45 control of timing devices carried on the locomotive, motor car, or other vehicle; but in order to make clear the important requisite of such a device, and to point out to better advantage the valuable characteris-

55 as forming a part of a complete train speed control system. The trackway equipment for such a system is shown in Fig. 1, and comprises in general a plurality of pairs of track elements or inductors which are distributed in the blocks of a block signaling system, or at, or near, points or zones of permanent hazard, such as yard limits, sharp curves, draw-bridges, etc., where restricted speed limits should always be observed irrespective of traffic conditions. While the general principle underlying this speed control system, can, of course, be applied to a large number of different forms 60 of block signal systems, or to control of speed limits for fixed hazards, in the simplified arrangement shown in Fig. 1, the track rails 1 are divided by insulated joints 65 2 into track sections or blocks in the usual way each having a track battery 3 and a track relay 4. The system may be used with, or without, the trackway fixed signals, and the signals may be of the semaphore, color-light, position light, or other suitable type; and in the simplified arrangement of Fig. 1, three-position semaphore signals X are shown conventionally, without any attempt to illustrate their well-known structure and control circuits, it being understood that these semaphores will 70 indicate, clear, caution, and stop in the usual way, dependent upon presence and absence of trains in the corresponding block 75 and the next block in advance.

80 Associated with each block are a number of pairs of track elements or inductors, three being shown in Fig. 1. The first element or inductor of each pair, comprises a core 5 of magnetic material of a general U-shape, and having enlarged pole pieces. The second track element of each pair has a coil 6 on its back yoke, and this coil 6 is included in a normally closed circuit of 85 low resistance opened and closed respectively at the front contact 7 of a line relay 8, when said relay is deenergized and energized. The line relays 8 for the several pairs of track elements are controlled by 90 the track relay 4 of the block next in advance, this control circuit being readily traced on the drawings. Thus, if the block 95 next in advance is not occupied, the second track element of each pair has its coil 6 100 105

in a closed circuit of low resistance, whereas, if said block in advance is occupied, the coils are open-circuited.

The car equipment shown in Fig. 2 has for its primary function the production of an automatic brake application in case the vehicle travels from the first track element of a pair to the second track element of that pair, when the latter has its coil 6 on open circuit and is in the active stopping condition, in less than a certain predetermined interval of time.

The several car-carried devices which cooperate through suitable circuits will first be separately referred to, after which the manner in which they cooperate will be described. On the railway vehicle or locomotive is provided a car element L which is adapted to cooperate with the track elements located along the track by having its pole pieces 10 move directly over the pole faces of the track elements. This car element L comprises a U-shaped core 9 of magnetic material terminating in pole pieces 10. This core is preferably laminated to increase its efficiency, and reduce the detrimental effect due to eddy currents. The forward leg of the U-shaped core 9 is provided with a primary or exciting coil P, the other leg being provided with a secondary or receiving coil S. This car element L is preferably mounted on a vehicle so that the pole pieces 10 have a definite relation to the track when the vehicle travels along the track, and is also preferably housed to protect it from snow, ice, moisture, and the like. This is preferably accomplished by housing the car element L in a suitable light non-magnetic casing, and by suspending this casing from the side frame of a truck or other suitable part having a definite relation with the track by an initially tensioned spring device.

On the vehicle is provided a control relay CR which is connected in circuit with the secondary coil S, and is adapted to be operated by current generated in the secondary coil; and in turn is adapted to actuate a repeater relay RR. This control relay CR and repeater relay RR have been conventionally illustrated, and in practice comprise a suitable winding adapted to actuate a well-balanced armature having contacts for cooperation with stationary contacts. In practice, the control relay CR is constructed very sensitive and operates small contacts; whereas the repeater relay RR is constructed with much heavier moving parts, and is provided with contacts for carrying a much larger current than are the contacts of the control relay. These relays are preferably mounted in a heavy casing supported by springs from the vehicle body. This construction causes the jars and vibration of the vehicle to be to a certain extent absorbed and transformed by the heavy casing, there-

by preventing such disturbances from reaching the relays and interfering with their operation.

A brake-setting or train control device K is employed which is of the normally energized type, and is constructed to apply the brakes a short time after it has been de-energized. This brake-setting device K has been illustrated conventionally by an electro-pneumatic valve having a winding 64. In practice, this brake-setting device K is constructed to pick up quickly, but drop slowly. This slow application feature may be obtained by providing an auxiliary timing device, such as, a dash-pot, inertia device or the like; or it may be obtained by providing a plurality of electro-responsive devices connected in a manner so that the inherent time of the sequential operation of the devices will be cumulative when deenergized, but will not be cumulative when energized. This brake-setting device K is of a character which makes a predetermined reduction of brake pipe pressure when deenergized, and is provided with means for preventing the engineer from opposing an automatic brake application, for instance, such as, by recharging the brake pipe, all in accordance with approved air brake practice. No specific structure for applying the brakes in this manner has been illustrated, since the specific form is not a part of the present invention, various forms of brake applying devices adaptable for this purpose being old in the art.

A reset switch RS has been provided which has been illustrated as a double-throw push button switch 11. This reset switch is provided for the purpose of allowing the engineer to remove the restriction caused by an automatic brake application, that is, release the brakes after the train has been brought to a stop. This device is preferably mounted on the railway vehicle so that it is only accessible from the ground, thereby preventing the engineer from resetting the brake control apparatus to normal immediately after an automatic brake application has been made. Further, this reset switch RS is protected against malicious tampering therewith, for instance, such as permanently fastening it in its depressed position. This is accomplished by completing the normally energizing circuit for the brake-setting device K through a back contact of the push button switch 11, thereby causing a permanent brake application if this push button switch 11 is fastened down.

A time controlled mechanism TM is provided constructed to cooperate with the quick pick-up and slow dropaway electricaly operated brake-setting device K, to apply the brakes when two successive control influences are received in less than a predetermined time; and which will accomplish

this function in a manner so that a failure of any of its essential elements will apply the brakes when a single influence is received, that is, it is constructed on the side 5 of safety. This time controlled mechanism TM has been illustrated in a simplified manner with a view of making it easy to understand its operating characteristics, rather than with the purpose of illustrating the 10 construction preferably employed in practice. This mechanism comprises a motor M which is designed to have constant speed characteristics, regardless of a slight change of voltage applied thereto, and has been illustrated 15 as a shunt motor, having an armature 12 and a shunt field winding 13, which is connected across a suitable source of E. M. F. illustrated as a battery 14. This motor M is connected to one member of a 20 suitable friction clutch FC by the shaft 16. This clutch may take any one of various forms, such as, an electro-magnetic clutch which is disengaged at certain times, or an electro-magnetic clutch of the induced current type wherein the torque transmitted depends on the induced current flowing in a 25 conducting member, but has been illustrated for convenience as a simple form of friction clutch FC. This clutch comprises a driving member 15 coupled to the driving shaft 16 and illustrated in the form of a cylinder; and a driven member or disc 17 pinned to a 30 shaft 18 to be driven.

On opposite sides of the disc 17 are friction washers 19 of fiber, asbestos fabric, or other suitable material; and these washers are pressed against the end of the cylinder 15, and opposite faces of the driven disc 17 by a spring 20 interposed between a follower plate 21 and an end member fixed to 40 said cylinder 15. The driven shaft 18 is provided with a worm 22 meshing with a worm wheel 23 keyed to a shaft 24 suitably supported in bearings.

To the shaft 24 is secured a member, conveniently termed a cam, which is shown as, 45 of a general circular form having a projection 26. Adjacent the cam 25 is supported on a suitable journal 27 a device which provides stops against which the projection 26 is adapted to abut, one of which is effective when this device is in its one extreme position and the other is effective when it is in 50 its other extreme position. This device has been illustrated as a pallet 28 of the shape shown. This pallet 28 is held in one position against the stop 29 by a releasing or time magnet 30, and is urged to its other extreme position when this releasing magnet 30 is deenergized by a spring 31.

Adjacent the cam 25 is mounted a circuit 55 closer comprising a switch blade 32 normally held by gravity or a spring, if so desired, against the back contact 33. This switch blade 32 is provided with an insulating roller

34 adapted to be actuated by the projection 26 when the cam 25 rotates about its axis, thereby causing the switch blade 32 to strike the front contact 35. Adjacent the pallet 28 is provided a stationary contact 36 and 60 a movable contact 37 which are normally held in contact with each other, but are adapted to be separated when the releasing magnet 30 is deenergized, by causing the insulating plug 38 to actuate the movable contact 37. 75

Operation.—Under normal conditions, that is, with the vehicle equipped with the apparatus illustrated in Fig. 2 moving in a clear block along a trackway system, such as illustrated in Fig. 1, the main control relay CR is maintained energized through a circuit, which may be traced as follows:—beginning at the terminal B of a battery, wire 39, movable contact 40 of the control relay CR, wires 41 and 42, winding of the control relay CR, wire 43, secondary coil S of the car element L, wire 44 to a common return wire C connected to the other pole of the battery. The current flowing in this 80 circuit is just sufficient to maintain the control relay CR in its energized position, allowing of course a margin to take care of variations, such as battery voltage, change of resistance due to temperature, and the like. 85

With the control relay CR in its energized position, the movable contact 40 will be moved in the position illustrated against the tension of the spring 45, thereby completing an energizing circuit for the repeater relay RR, which may be traced as follows:—beginning at the terminal B of a battery, wire 39, movable contact 40, wire 46, winding of the repeater relay RR, wire 47 back to the common return wire C. 90 95

With the repeater relay RR energized, its armature will be attracted against the tension of the spring 48, thereby completing a circuit which may be traced as follows:—beginning at the terminal B of a battery, wire 49, movable contact 50 of the repeater relay RR, wire 51, winding of the releasing magnet 30, wire 52 back to the common return wire C. The energization of the releasing magnet 30 causes the pallet 28 to bear 100 105 against the stop 29. 110

Assume now that the motor M is energized, thereby causing the projection 26 of the cam 25 to bear against the stop member 53 of the pallet 28, thus holding the cam 25 stationary while the motor M is rotated, causing a definite torque to be applied to the cam member 25 through the slipping friction clutch FC. Further, the energization of the releasing magnet 30 closes an exciting circuit by allowing the movable contact 37 to engage the stationary contact 36. This exciting circuit may be traced as follows:—beginning at the terminal B of a battery, wire 54, push button 11, wire 55, switch blade 32, 115 120 125 130

back contact 33, wire 56, stationary contact 36, movable contact 37, wire 57, winding 64 of the brake-setting device K, wire 58, primary coil P of the car element L, wire 59 5 back to the common return wire C. With this exciting circuit energized, a magnetomotive-force will be set up in the primary winding tending to send flux through the core 9 of the car element. Very little flux 10 will, however, pass through the secondary coil S on account of the large air gap between the pole pieces 10. The completion of this exciting circuit also energizes the normally energized brake-setting device K, 15 thereby putting the brakes in their inactive condition, allowing the train to proceed without interference.

Assume now that a train equipped with the apparatus illustrated in Fig. 2 in its 20 normal condition passes over a track element in its active stopping condition, that is, with the coil 6 thereon open-circuited if the track element in question has such a coil. Under such conditions, a large amount of 25 flux will permeate the core 9 of the car element, thus causing a rapid increase of flux through the secondary coil S. This change of flux, it is believed, is partly due to diversion of flux from leakage paths around the 30 primary coil P through the secondary coil S, and partly due to an increase of the total flux through the core 9, due to the decrease of reluctance of the magnetic circuit. As the car element recedes from the track element, the flux again changes back to its 35 initial value. Such rapid increase and decrease of flux through the secondary coil S induces a single cycle of voltage therein similar to that of an alternating current. The 40 secondary coil S is preferably so connected in the energizing circuit of the control relay CR that the first wave of said cycle of induced voltage is in a direction to oppose the voltage of the battery in said circuit, thereby reducing the current in said circuit sufficient to cause the control relay CR to drop 45 its armature. While the current change is only momentary, the control relay CR will, however, be permanently deenergized, because its energizing circuit is interrupted by the opening of its front contact when its armature is momentarily retracted.

Assume now that the train passes over a 50 track element provided with a coil 6, and that this coil is included in a circuit of low resistance. As the car element L passes over the track element in this inactive condition, no control influence will be transmitted to the control relay CR. This is believed to be due to the bucking action of the coil 6 of the track element which is now closed in a circuit of low resistance. For instance, as the car element L passes over the second track element with its coil in a circuit of low resistance, a very slight penetration of flux

through the track element causes a large current to be set up in the winding 6. This current, in accordance with well-known principles, flows in a direction to oppose the magnetism producing it, thereby preventing 70 very little further change of flux. This slight change of flux through the track element also produces a slight change of flux in the winding of the secondary coil of the car element. This slight change of flux, 75 however, induces insufficient voltage in the secondary coil to actuate the control relay CR.

As previously explained, the first track element of each pair in each block, as shown 80 in Fig. 1, is preferably constructed without any coil, so as to constitute an inert body of iron; whereas the second track element of each pair has a coil 6 which is in closed circuit normally, that is, when the block next 85 in advance is not occupied, and is in open circuit under danger conditions when said block in advance is occupied. Consequently, under danger conditions, a passing car receives at each pair of track elements two 90 successive controls or influences, these influences being received one after the other in an interval of time which depends upon the speed of the train and the distance said track elements are apart. In practice, the 95 track elements of each pair are spaced apart a distance corresponding to the speed limit it is desired to enforce at that particular point; and as indicated in the diagram 100 shown in Fig. 1, the track elements are spaced relatively closer together near the exit end of the block than at the entrance end. Under clear traffic conditions, since the coil 6 of the second track element of each pair is in a 105 closed circuit, a passing car receives only one influence at each pair of track elements. It may be added that, if desired, the first track element of each pair may also be provided with a coil 6, so that under clear 110 traffic conditions it will not communicate a stopping influence.

Considering now the operation of the car equipment, it may be explained at the outset that this equipment is intended to produce an automatic brake application, by acting upon the regular brake equipment of the car, in case two successive influences are communicated to the car in less than the predetermined time for which the timing mechanism is constructed or adjusted. The present invention deals more particularly with the construction of the timing mechanism and the provisions made to assure that any failure of said mechanism to operate 115 properly will be automatically detected, the 120 brakes applied, and the car controlled on the side of safety.

Assume that the car with its equipment in the normal condition, as shown in Fig. 2, 125 passes over the first track element of a pair.

This track element, as previously explained, produces a change of flux in the secondary coil S, and causes the main control relay CR to become deenergized. The deenergization of the control relay CR causes the repeater relay RR to be deenergized, and this relay RR in turn deenergizes the releasing magnet 30. This causes the pallet 28 to be moved by the spring 31, thereby actuating the movable contact 37 to open the exciting circuit through the brake-setting device K heretofore traced. Since the brake-setting device is slow acting when deenergized, it will not apply the brakes immediately. As the pallet 28 moves away from the stop 29, the stop member 53 releases the projection 26, thus allowing the cam 25 to be rotated by the motor M through the friction clutch FC. As the projection 26 strikes the roller 34 the switch blade 32 is brought in contact with the front contact 35, thereby energizing a pick-up circuit for the control relay CR, which may be traced as follows:—beginning at the terminal B of a battery, wire 54, push button switch 11, wire 55, switch blade 32, front contact 35, wires 60, 61 and 42, winding of the control relay CR, wire 43, secondary coil S, wire 44 back to the common return wire C. This causes the control relay CR to be momentarily energized, thereby completing its stick circuit, heretofore traced, which will keep it permanently energized.

The control relay CR again being energized causes the repeater relay RR and in turn the releasing magnet 30 to be energized thus again closing the exciting circuit through the brake-setting device K, in time to prevent this device K from applying the brakes. Thus, the train is moving between the track elements of the pair and the cam 25 of the time controlled mechanism is rotating in the direction of the arrow.

For the first condition to be considered, assume that a predetermined speed limit is to be enforced, and that the coil 6 of the second track element of the pair is on open circuit, so that said second track element produces another operation on the control relay CR. If the train is traveling at less than the desired speed limit, the brakes are not applied; whereas if the train is traveling at a speed higher than the desired speed, the brakes are automatically applied.

Assume first that the car is traveling at less than the desired speed limit. The car, then, in traveling from the first track element to the second track element will take more time than that for which the timing mechanism on the car is constructed or adjusted; and consequently before the control relay CR drops the second time at the second track element of the pair, the cam 25 will have completed its cycle of operation, making one complete revolution back

to the normal position shown in Fig. 2, where it is stopped by the engagement of the projection 26 with the pallet or detent 28. When the control relay CR drops the second time, therefore, the timing mechanism is 70 merely set into operation again; and if the timing mechanism works properly, the relay CR is reset, as previously explained, and no brake application occurs. It is noted here that the space between the second element of a pair and the first element of the next pair in the direction of traffic must be long enough such that the train, running at the proper speed, will take more time in traveling between these track elements than that for which the timing mechanism is adjusted, otherwise an automatic brake application might be improperly produced by the action of the first and last track elements of two succeeding pairs, in the same 80 way as the track elements of the same pair produce such control, as about to be explained.

Assume now that the car is traveling at a speed higher than the desired speed limit. 90 Under these circumstances, the car will travel over the space between the two track elements of the pair in less than the time for which the timing mechanism is set; and consequently at the instant the control relay CR drops the second time at the second track element, the cam 25 has not had time to come back to its normal position, as shown. Consequently, when the control relay CR drops, the repeater relay RR is de-energized, and the releasing magnet 30 is deenergized to allow the detent member 28 to be shifted by the spring 31, the projection 26 on the cam 25 having not passed the stop arm 62 of said detent member. As previously explained, when the releasing magnet 30 is deenergized and the detent member 28 released, the contacts 36—37 are opened to cut off energizing current from the train control device K; and unless such energizing current is re-applied in less than an interval of time, said device K acts to apply the brakes or produce any other desired control.

Under the particular conditions assumed, the cam wheel is arrested by the stop arm 62, at the time the releasing magnet 30 is deenergized; and hence the switch arm 32 is not actuated in the manner of its normal operation, with the result that the control relay CR is not picked up, the repeater relay is not re-energized, and the releasing magnet 30 is not again energized to reclose contacts 36—37, within the limited time it takes the device K to become effective. Thus, if the car reaches the second track element of the pair in question before the timing mechanism has completed its cycle of operation, there is no resetting of the control relay CR and devices governed thereby, and 130

- after a time, the brakes are automatically applied by the device K. Furthermore, this condition of the devices continues or persists until the apparatus is reset by hand.
- 5 It should be noted that under certain speed conditions an impulse may be received at the time the projection 26 has passed beyond the stop arm 62 but has not yet reached the stop member 53. In this case, the brakes
- 10 will not be effectively applied, nor the train be effectively controlled in any other way, although the device K may assume its de-energized condition momentarily (depending on the slow acting characteristic of this
- 15 device K) because the projection 26 will again strike roller 34 and restore the devices CR, RR and 30, thereby re-energizing the train control device K and finally stopping the cam 25 in its normal position. The slow
- 20 acting feature of this device K is preferably such that it will not reach its deenergized condition in the assumed case. This is, however, not absolutely necessary to make it a practical system.
- 25 After the train has been brought to a stop in a manner as just explained, the engineer may remove the restriction caused by the brake-setting device K by operating the push button 11 which is only accessible from
- 30 the ground. By actuating the push button 11, a pick-up circuit for the control relay CR will be completed, which may be traced as follows:—beginning at the terminal B of a battery, wire 54, push button switch 11,
- 35 wires 63, 61 and 42, winding of the control relay CR, wire 43, secondary coil S, wire 44 back to the common return wire C. This causes the control relay CR to be permanently energized through its stick circuit,
- 40 thereby energizing the repeater relay RR which in turn energizes the releasing magnet 30, which rocks pallet 28 to allow the cam 25 to advance until projection 26 strikes stop member 53, ready for next operation, and also to permit the movable contact 37 to come into contact with stationary contact 36. The brake-setting device K will, however, not be energized until the push button 11 is again released by the engineer, since its energizing circuit has been interrupted at the back contact of the push button 11. This arrangement is provided so that the engineer can not tie the push button 11 into its resetting position permanently, thereby allowing him to defeat the purpose of the speed control system.
- 45 If the coil 6 of a second track element of the pair is in a closed circuit of low resistance, a control relay CR on the passing vehicle is not operated; and consequently, irrespective of whether the timing mechanism has completed its cycle of operation or not, no brake application occurs. Thus, under
- 50 clear traffic conditions, while the timing mechanism is set into operation by the first

track element of each pair, no speed limitations are enforced, and no automatic brake applications occur, except in the event of a failure of the timing mechanism to operate properly, as hereinafter explained.

70 The important features of this invention relate to the provision made to assure detection of failure of the timing mechanism to operate properly. Referring to Fig. 2, and bearing in mind the operation of setting the cam 25 into motion, it will be observed that unless said cam actually starts and moves the switch arm 32 against its back contact 35, then the device K, which is de-energized by the opening of the contacts 36—37, causes an automatic brake application after a time. Consequently, if the motor M is not working, due to some breakage or failure of the battery 14, or the friction clutch FC is not functioning properly, or in 75 fact any of the driving connections of the cam 25 are broken or fail to operate, then such failure is automatically detected and is manifested by a brake application. The releasing magnet 30, being a normally energized device, may be depended upon to perform its desired functions; and it will be evident that in case of breakage of wires, failure of the battery, or the like, detent member 28 is shifted or retracted by the 80 spring 31, and opens contacts 36—37 permanently, with the result that the brakes will then be automatically applied as soon as the device K has had time to operate, irrespective of the fact that the cam has been released and operated switch arm 32 to reset the control relay CR and the repeater relay RR.

85 It will be noted that the energizing circuit for the train control device K includes a normally closed front contact 33 of the switch arm 32; and hence, if this switch arm should for any reason stick in the operated position (shown in dotted lines), so as to close the pick-up circuit for the control relay CR, then the brakes will be automatically applied on account of the permanent deenergization of the control device K. For this reason the switch arm 32, after each movement thereof, must return to its normal 90 position shown, otherwise a brake application occurs. In short, it can be seen that all of the operating parts controlling or controlled by the timing mechanism are either normally energized, so that failure results in a control on the side of safety, or else have their operation automatically checked.

95 It should also be observed that the reset switch RS permits restoration of the car equipment to the normal condition, in case 100 the brake application is due to excessive speed; whereas, if the brake application is due to a failure of some of the parts and circuits, such brake application will persist 105 or be repeated at each active track element,

regardless of speed, and in spite of the operation of the reset switch RS.

It should be noted that the functioning of the automatic speed control system just described depends upon the presence of a certain amount of magneto-motive-force in the car element L. In order to check the presence of the necessary magneto-motive-force, the brake-setting device K has been included 10 in series with the primary coil P. The brake-setting device K is so designed that if the current in the exciting circuit falls to a value to produce insufficient magneto-motive-force in the car element L to actuate the control relay CR under normal conditions, that the brake-setting device K will be deenergized, thus applying the brakes regardless 15 of influences transmitted from the trackway. It should be noted that both the trackway apparatus and the car-carried apparatus have been designed and constructed so that a failure of any part, which is likely to occur and commonly experienced in practice in course of time, will cause an automatic brake application upon such failure.

Another characteristic feature of the particular type of speed control system disclosed is that, immediately upon a change in traffic conditions ahead, the speed restrictions enforced by the pairs of track elements are automatically removed. For example, suppose that a train is in the block I approaching the second pair of track elements shown, and is reducing speed to avoid 20 a brake application, because there is another train ahead in the block J. If, now, the train ahead leaves the block J, the signal X¹ at the entrance to that block changes to the caution position, signifying to the engineer that he may resume speed; and at 25 the same time the line relays 8 are energized to close the circuit for the coil 6 of the second track element of each pair, so that the train may travel at any speed by said pairs 30 of track elements without receiving automatic control. Such automatic release of the speed limits imposed in a caution block as soon as traffic conditions in the next block 35 in advance clear up is important from a standpoint of facilitating train movement, since it allows a train to accelerate as soon 40 as conditions ahead change and permit such acceleration. Also, in case there is a change 45 in traffic conditions in the next block in advance after a train has entered a block, the second track element of each pair will be 50 put in the active stopping condition, with the result that the brakes are applied, if the 55 train in said block is exceeding the safe speed at these respective pairs of track elements.

These features of automatic release, or 60 automatic enforcement of train control, in the event of a change in traffic conditions in advance, are characteristic of the type of

system to which the present invention relates, but aside from their combinational relation to the features of the present invention, no claim thereto is made herein.

Although only one specific embodiment of the present invention has been illustrated, both with regard to the trackway apparatus and the car-carried apparatus, it should be understood that various modifications may be used to adapt the invention to the various conditions encountered in practice without departing from the spirit and scope of the present invention. For instance, the trackway devices may be controlled in any suitable manner, dependent upon the block signal system in connection with which they are used, for instance, an entirely automatic system, or an auto-manual system with the employment of various sources of current; or pairs of permanently active track elements each comprising a core similar to the core 5 may be employed where permanent hazards, such as, short curves, approaches to bridges, yard limits, and the like, are existing along the trackway. Further, the car-carried apparatus may be modified to apply it to the various trackway systems commonly employed. For instance, the necessary modifications may be made so that the same apparatus can be used when either end of the vehicle is running ahead, either for double track or single track systems, so that no control influence will be received when running against traffic in either case, as is obvious to those skilled in the art.

Having now fully shown and described my invention, what I desire to secure by Letters Patent, is:—

1. In a train control system, the combination with a pair of spaced track devices, automatic brake-setting apparatus on a vehicle acting upon the regular brake equipment thereof and having its operation dependent upon the speed of the vehicle in passing between said track devices, said apparatus being influenced by said track devices and comprising, a brake-setting device, a normally energized stick relay which if deenergized tends to actuate said brake-setting apparatus, a normally inactive time controlled mechanism automatically set into operation by said relay when said relay is influenced by a track device for removing the tendency to actuate said brake-setting device, whereby failure of said mechanism to become active in response to the actuation of the relay by a track device causes an automatic application of the brakes.

2. Brake control mechanism acting upon the usual braking equipment on a railway vehicle comprising, a brake-setting device, control means including a time controlled device maintained inactive by a normally energized winding adapted to be influenced from the trackway for actuating said brake.

- setting device if two successive control influences are received in less than a predetermined time, and also including means for actuating said brake-setting device if said time controlled means fails to start to operate due to deenergization of said winding.
3. Brake control mechanism acting upon the usual braking equipment on a railway vehicle comprising, a brake-setting device, a time controlled means, control means adapted to be influenced from the trackway for starting said time controlled means through a period of operation and for actuating said brake-setting device, said time controlled means restoring said brake-setting device if a single control influence only is received before said time controlled device has completed its period of operation,
- 10 20 25 30 35 40 45 50 55 60 65 70 75 80 85 90 95 100 105 110 115 120 125
- 20 whereby control means actuates said brake-setting device if said controlled means fails to operate.
4. Brake control mechanism acting upon the regular braking equipment of a railway vehicle comprising, a normally energized slow releasing brake-setting device, a time controlled device, control means governed from the trackway for starting said time controlled means and for deenergizing said brake-setting device at the same time, and means effective only after said time controlled means has commenced its operation for energizing said brake-setting device before it has become effective.
- 25 30 35 40 45 50 55 60 65 70 75 80 85 90 95 100 105 110 115 120 125
- 35 5. Brake control mechanism acting upon the regular air brake equipment of a railway vehicle comprising, a normally energized and normally inactive slow acting brake-setting appliance, control means actuated by influences received from the trackway for deenergizing said brake setting appliance which control means if deenergized remains deenergized until restoration, means set into operation by said control means upon the reception of a control influence for restoring said control means to normal, said last mentioned means being ineffective to restore said control means if said control means is operated twice in succession within less than a predetermined interval of time.
- 40 45 50 55 60 65 70 75 80 85 90 95 100 105 110 115 120 125
- 60 65 70 75 80 85 90 95 100 105 110 115 120 125
6. Automatic train control apparatus comprising, a slow acting brake-setting device acting upon the usual braking equipment on a railway vehicle, means including a rotatable member controlled by influences from the trackway for actuating said brake-setting device if two successive control influences are received in less than a predetermined time, said means including means for actuating said brake-setting device if said member fails to start into operation in response to an influence.
- 65 70 75 80 85 90 95 100 105 110 115 120 125
7. Brake control mechanism acting upon the regular air brake equipment of a rail-
- way vehicle comprising, a normally energized and normally inactive slow acting brake setting appliance of the type which if deenergized remains deenergized until restored, control means actuated by influences received from the trackway for deenergizing said brake-setting appliance, means set into operation by said control means upon the reception of a control influence effective to restore said control means and in turn restore said slow acting brake-setting appliance to normal before said appliance has assumed its active condition, said last mentioned means being ineffective to restore said control means to normal if said control means is operated twice in succession within less than a predetermined interval of time.
8. Automatic train control apparatus comprising, a slow acting brake-setting device acting upon the usual braking equipment on a railway vehicle, means controlled by influences from the trackway for initiating the actuation of said brake-setting device, a movable member urged to move at a definite speed, and means actuated by said member for preventing said brake-setting device becoming active if the successive control influences are separated more than a predetermined interval of time.
9. An automatic train control system comprising, a brake-setting device acting upon the usual automatic braking equipment of a railway vehicle, means controlled by influences received from the trackway for actuating said brake-setting device if two successive influences are received in less than a predetermined time and including a time element device normally held against movement and performing a cycle of operation if initiated, said means being constructed to cause said brake-setting device to be actuated if said time element device is released but does not start to operate.
10. Train control apparatus for railway vehicles comprising, a brake-setting appliance, a normally inactive time controlled device having a normal condition, control means for initiating a change of said device from its initial position and at the same time initiating operation of said appliance, and means effective only after the time controlled device has actually changed from its normal condition for restoring said appliance, whereby the operation of the time controlled device is automatically checked and failure thereof produces a brake application.
11. In a train control system of the type described, a movable member, releasable means normally maintaining said member stationary, means tending to move said member at a predetermined rate of speed, and automatic means manifesting failure of said member to move when released.
12. In a train control system adapted to

- determine the application of the brakes on railway vehicles dependent upon the time taken by such vehicles to traverse the space between two successive control points comprising, a rotary member, means for moving said member from an initial position back to that position in a certain interval of time, releasable means adapted to be influenced from the trackway for holding said member in its initial position, and automatic means for applying the brakes of the vehicle whenever said member is released and fails to rotate. 5
13. In a train control system adapted to determine the application of the brakes on railway vehicles dependent upon the time taken by such vehicles to traverse the space between two successive control points comprising, a normally energized brake-setting appliance, a time element device, automatic control means adapted to be influenced from the trackway for simultaneously setting the time element device into operation and de-energizing the brake-setting appliance, and automatic means effective only after the time element device commences its operation for re-energizing said appliance. 10
14. In a system of train control of the general character described, a time element device having a normal condition and when set into operation automatically returning to that condition after a lapse of a predetermined time, means conditioning said device for operation, and means preventing it returning to its normal condition if again conditioned in less than a predetermined time. 15
15. Train control apparatus for railway vehicles comprising, a normally energized brake-setting appliance adapted when de-energized to cause an automatic application of the brakes, an energizing circuit for said appliance, an element movable from an initial position back to that position in a predetermined time, control means responsive to influences from the trackway for simultaneously initiating the movement of said element and for breaking said energizing circuit at one point, and a circuit controller shifted temporarily by the movement of said element near its initial position, said circuit controller while shifted opening said energizing circuit at another point and also acting to restore the control means to normal. 20
16. Car-carried apparatus for automatic train control systems of the type in which the brakes are automatically applied after two successive control influences are received in less than a predetermined interval of time comprising, a normally energized brake control device, a time element device, a normally energized electro-responsive device having a contact closed when said electro-responsive device is energized which contact is included in the energizing circuit of said brake control device for directly maintaining said brake control device inactive and having means associated therewith for maintaining said time element device in its normal condition, said time element device including means for re-energizing said electro-responsive device only once during the time of each operation of said time element device, and means accessible only from the ground for restoring said electro-responsive device to normal. 25
17. Speed responsive brake control apparatus on a railway vehicle of the general type described comprising, a movable element, a constant speed motor tending to drive said element, releasable means maintaining said element in an initial position, and automatic brake applying means having its operation initiated when said releasable means is actuated to release said element and causing an automatic brake application if said element fails to move. 30
18. Apparatus for governing the regular braking equipment of railway vehicles dependent upon the speed thereof at predetermined points along the track comprising, a normally energized control means of the type which if momentarily deenergized remains deenergized until restored and located on the vehicle and actuated by inductive control influences transmitted from the trackway, a normally energized and normally inactive slow acting brake setting appliance adapted to have its energizing circuit broken by operation of said control means, a time element device, and normally open contacts controlled by said device for restoring said control means to normal, said normally open contacts when closed by said time element device restoring said control means and in turn re-energizing said slow acting brake setting appliance before said appliance has assumed its active condition and said open contacts if closed breaking the energizing circuit for said brake setting appliance, whereby accidental displacement of said contacts into the restoring position cannot effect permanent energization of said appliance. 35
19. An automatic train control system for railways comprising, car-carried apparatus for controlling the speed of the train including a rotatable device set into operation in response to control influences transmitted inductively from the trackway, a normally energized brake-setting appliance which if deenergized applies the brakes of the train, a normally energized electro-responsive device for maintaining said rotatable device and said brake-setting appliance inactive, a stick relay for controlling said appliance, and movable means for picking up said stick relay by rotation of said rotatable device upon deener. 40

- gization of said electro-responsive device, whereby failure of said rotatable device to rotate upon deenergization of said electro-responsive device causes the brakes to be 5 automatically applied.
20. Automatic brake control apparatus for railway vehicles of the general type described comprising, means for receiving control influences from the trackway, a time controlled mechanism having a normally open circuit controller closed once for each influence received by said mechanism providing the lapse of time between successive influences is more than a predetermined 10 interval of time, and automatic means manifesting closure of said circuit controller for more than a certain time interval.
21. Brake control equipment for railway vehicles dependent upon the speed thereof at predetermined control points along the track comprising, a rotary member, means to drive said member at a constant rate, control means for holding or releasing said member and adapted to be influenced from 15 the trackway for arresting movement of said member at a predetermined point, and automatic means for applying the brakes if said member fails to move when released by the control means.
22. Brake control equipment for railway vehicles dependent upon the speed thereof at predetermined control points along the track comprising, a time element device changeable from a normal position and automatically returning to that position after a 20 lapse of a predetermined time, and control means adapted to be influenced from the trackway for permanently arresting the change of said device whenever two successive operations of said control means occur 25 within less than said predetermined time.
23. Brake control equipment for railway vehicles dependent upon the speed thereof at predetermined control points along the track comprising, a slow acting brake-setting appliance, a time element device changeable from an initial position back to that position after the lapse of a predetermined 30 time, a stick relay deenergized by influences received from the trackway for initiating operation of the brake-setting appliance and at the same time setting the time element device into operation, and automatic means 35 effective only after the time element device has partially changed for picking up the stick relay and thereby restoring the brake-setting appliance.
24. An automatic train control system for railways comprising, car-carried apparatus for controlling the speed of the train including a rotatable device set into operation in response to control influences transmitted inductively from the trackway, a normally energized brake setting appliance which if 40 deenergized applies the brakes of the train, a normally energized electro-responsive device for maintaining said rotatable device and said brake setting appliance inactive, a stick relay for controlling said appliance, and movable means for picking up said stick 45 relay by rotation of said rotatable device upon deenergization of said electro-responsive device, said movable means while in its pick-up position cutting energy off of said brake setting appliance, whereby accidental displacement of said movable means into the pick-up position effects an automatic 50 brake application.
25. An automatic train control system comprising, a rotatable time element device normally tending to rotate but maintained in its normal condition by a normally energized stick electro-responsive device and adapted to perform a predetermined cycle of operation if deenergized during which 55 cycle it is capable of only once picking up said stick electro-responsive device, and normally energized brake control means governed by said electro-responsive device.
26. An automatic train control system comprising, a car-carried relay normally energized by a circuit including a front contact of said relay, a time element device governed by said relay having a normally energized coil for maintaining said device inactive and which coil if deenergized allows said time element device to perform a predetermined cycle of operation, and means governed by said time element device for closing a pick-up circuit for said relay.
27. An automatic train control system comprising, a normally energized stick relay, inductive influence communicating means partly on the vehicle and partly along the trackway for transmitting control influences to actuate said relay, a rotatable time element device normally tending to operate but maintained in its normal condition by a normally energized electro-responsive device and adapted to perform a predetermined cycle of operation if said electro-responsive device is deenergized said time element device closing a pick-up circuit for said stick relay in said cycle of operation, and normally energized brake control means governed by said time element device.
28. An automatic train control system comprising, a control relay normally energized by a circuit including a front contact of said relay, a normally energized brake control device; and a time element device including means rotatable about an axis tending to move from its normal position, said time element device including a normally energized coil controlled by said control relay maintaining said rotatable means in its normal position and allowing it to complete a

cycle of operation if momentarily deenergized, and including means for picking up said control relay.

29. Automatic train control apparatus comprising, a slow acting brake-setting device acting upon the usual braking equipment on a railway vehicle, means controlled by influences transmitted from the trackway for initiating the actuation of said brake-setting device, a movable member urged to move through a certain cycle of operation, and means actuated by said member for preventing said brake-setting device becoming active if the successive control influences are separated by more than a predetermined interval of time.

30. An automatic train control system comprising, a pivotally supported member normally held against rotary movement, means tending to assume a condition to permit actuation of said member through a certain cycle of operation, means tending to move said member, automatic means manifesting failure of said member to move when released, and inductive influence communicating means located partly on the vehicle and partly along the trackway for governing said first mentioned means.

31. An automatic train control system comprising, a slow acting brake-setting device acting upon the usual braking equipment of a railway vehicle, means controlled by influences transmitted from the trackway for initiating the actuation of said brake-setting device, a movable member controlled by said means urged to perform a certain cycle of operation in a certain period of time, and means actuated by said member for preventing said brake-setting device from applying the brakes if the successive influences transmitted are separated by a predetermined space of time.

32. An automatic train control system for railways comprising, car-carried apparatus for controlling the speed of the train including a rotatable device set into operation in response to control influences transmitted from the trackway, a normally energized slow acting electro-pneumatic valve which if deenergized applies the brakes of the train after an interval of time, a stick relay for controlling said valve, and movable means for picking up said stick relay by rotation of said rotatable device upon deenergization of said electro-responsive device, whereby failure of said rotatable device to rotate upon

deenergization of said electro-responsive device causes the brakes to be automatically applied after said interval of time.

33. An automatic train control system comprising, a normally energized brake-setting device acting on the usual air brake system which device applies the brakes when deenergized, normally energized apparatus controlling said brake-setting device and rendered effective until reset if momentarily deenergized, a time element device for resetting said apparatus effective to reset said apparatus once in a predetermined period of time only, and manually operable means accessible only from the ground for resetting said apparatus.

34. An automatic train control system for railways comprising, car-carried apparatus for controlling the speed of the train including a rotatable device set into operation in response to control influences transmitted inductively from the trackway, a normally energized brake setting appliance which if deenergized applies the brakes of the train, a normally energized electro-responsive device for maintaining said rotatable device and said brake setting appliance inactive, a stick relay for controlling said appliance, movable means for picking up said stick relay by rotation of said rotatable device upon deenergization of said electro-responsive device, whereby failure of said rotatable device to rotate upon deenergization of said electro-responsive device causes the brakes to be automatically applied, and means accessible only from the ground for restoring said apparatus to normal, said last mentioned means functioning only to restore said apparatus if it is moved to its restoring position and is then returned and left in its normal position.

35. Trackway equipment for enforcing speed restrictions through a block by suitable car-carried train control apparatus comprising, a trackway including the usual track rails, and a plurality of pairs of track elements spaced relatively close together at different distances apart and located outside of the track rails at intervals in the block, one element only of each pair having a coil thereon closed in a deenergized circuit of low resistance when there are no trains in the block next in advance.

In testimony whereof I hereto affix my signature.

CHARLES S. BUSHNELL.
